UNITED STATES PATENT OFFICE.

ROY SHERMAN, OF TOLEDO, OHIO.

SHINGLE-HOLDING MEANS.

Application filed August 2, 1922. Serial No. 579,177.

To all whom it may concern:

Be it known that I, ROY SHERMAN, a citizen of the United States, and a resident of Toledo, in the county of Lucas and State 5 of Ohio, have made an Invention Appertaining to a Shingle-Holding Means; and I do hereby declare the following to be a full, clear, and exact description of the invention, such as will enable others skilled 10 in the art to which it appertains to make and use the same, reference being had to the accompanying drawings, and to the characters of reference marked thereon, which form a part of this specification.

15 This invention relates to roofing construction, and particularly to a locking or securing means for the exposed ends of shingles of a flexible nature, such for instance, as what are commonly known as 20 asphalt shingles.

25 In the laying of certain types of shingles of this character it is customary to place their edges at an angle to a horizontal, with the lower points thereof lapping the adjacent side points of adjoining shingles, and the upper point portion of another shingle, or, in other words, the shingles are laid in 30 diamond form. With this arrangement the lower exposed pointed portions of the top shingles, unless locked or secured down in some manner, will be lifted up by the wind and permit rain and snow to beat thereunder.

35 The object of this invention is to provide simple, efficient and inexpensive means for firmly securing an exposed shingle point in place, and which is capable of easy and quick application.

40 The invention is fully described in the following specification, and while, in its broader aspect, it is capable of embodiment in numerous forms, a preferred embodiment thereof is illustrated in the accompanying drawings, in which,—

45 Figure 1 is a plan of a fragmentary section of a shingle covering for a roof embodying the invention. Fig. 2 is an enlarged section on the line 2—2 in Fig. 1, and Fig. 3 is a perspective view of the 50 locking device.

55 Referring to the drawings, 1 designates each of a plurality of shingles of a roof, which shingles are of a pliant or flexible nature and of rectangular form, substantially square in the present instance, and have one corner cut off at 2 to form a like angle

with each of the adjoining or intersecting sides. The purpose of my invention is to hold the lower exposed chamfered corners of the shingles down to the roof when the 60 shingles are laid in what may be termed diamond form or with their edges diagonally disposed with respect to a horizontal. In laying the shingles in this manner, each pair of side adjoining shingles, for instance, 65 *a* and *b*, have their adjacent pointed side corners meeting at a point *c* in lapping relation over the upper side edge portions of a subjacent shingle *d*, and a shingle *e* of the next row in order is positioned with 70 its center over the point *c*, with its lower side edges lapping the adjacent side edges of the shingles *a* and *b*, and with its lower chamfered edge 2 extending below the point 75 *c* and disposed in a horizontal plane. When the next row of shingles has been placed 80 over the row of shingles *e* in alternating relation thereto it is apparent that the lower chamfered end portion of the shingles *e* will be exposed to the weather and subject 85 to being raised by wind pressure thereunder.

To prevent such raising of the lower exposed end portions of the shingles I provide a thin plate or cross-member 3, which 90 is adapted to lap the adjoining side corners of adjacent shingles of a row over a point *c* and has perforations 4 therein near its ends to receive retaining nails, which are intended to be driven through the plate 3 and the subjacent portions of the shingles, *a*, *b* and *d* over which it is disposed, and then into the roof sheathing, or into the old shingles on the roof if the new shingles 95 are laid thereover, as is frequently done. The plate 3 is provided at its central portion with an upstanding stud or stem 5 of a bendable nature which is intended to be projected up through a registering aperture 6 in the exposed lower end portion of 100 a superposed shingle and is then bent over against the outer side of such shingle to cooperate with the plate 3 and securing nails 7 to firmly hold or lock the exposed shingle end to the roof. With this locking means 105 it is not necessary to nail the shingles at any other points to the roof, as each shingle has three plates 3 disposed thereover and secured to the roof by four nails 7, as is apparent. It is thus evident that the locking 110 means employed not only provides a means for securely locking the free end por-

tion of a shingle against raising under wind pressure, but also effectively secures the shingles to a roof.

I wish it understood that my invention is not limited to any specific construction, arrangement or form of the parts, as it is capable of numerous modifications and changes without departing from the spirit of the claim.

Having thus described my invention, what I claim as new, and desire to secure by Letters Patent, is,—

In a roof construction having shingles of rectangular construction arranged in such a manner that one shingle overlaps portions of two subjacent shingles, means for hold-

ing the shingles together consisting of a flat metallic strip adapted to be inserted between the upper shingle and subjacent shingles, a central upwardly extending bendable stem on the strip projecting thru said upper shingle and adapted to be bent over upon the upper surface thereof, and downwardly extending elements adjacent the opposite ends of the strip for securing the strip to the subjacent shingles, thereby securely retaining three shingles in assembled relation without the necessity of additional securing means.

In testimony whereof, I have hereunto signed my name to this specification.

ROY SHERMAN.
